TOWEL RACK OR SIMILAR ARTICLE

Albert Spielman, New York, N. Y., assignor to Sanjo Utility Manufacturing Co., Inc., Brooklyn, N. Y., a corporation of New York

Application April 1, 1958, Serial No. 50,273

Term of patent 7 years

(Cl. D4—3)

Fig. 1

Fig. 2

Fig. 3

Fig. 4

Figure 1 is a view in perspective of a towel rack or similar article, showing my new design;

I claim:

The ornamental design for a towel rack or similar article, substantially as shown.
